VEHICLE DOOR LATCH

Holden W. Rightmyer, Toledo, Ohio, assignor to
 The American Swiss Company, Toledo, Ohio,
 a corporation of Ohio

Application November 26, 1937, Serial No. 176,572

4 Claims. (Cl. 292—164)

This invention relates to vehicle door latches and an object is to produce a door latch having the new and improved features of construction, arrangement and operation hereinafter described.

5 An embodiment of the invention is shown by way of illustration on the accompanying drawing in which

Figure 1 is a top plan view of a vehicle door latch, the inside operated remote control structure being omitted and a portion of the cylinder locking device being broken away;

10 Figure 2 is a side edge elevation of the lock shown in Figure 1; and

15 Figure 3 is a plan view of the dogging plate for the outside operated roll back.

The illustrated embodiment of the invention comprises a vehicle door latch having a case plate 10 provided with an outwardly extending flange 11 at one edge. Formed in the flange 11 is a suitable opening through which extends the nose 12 of a latch bolt 13. The nose 12 is secured to the latch bolt by rivets 14 and bearing against the rear face of the bolt nose is the free end of a spiral spring 15, the opposite end of which is secured by ears 16 struck out of the case plate 10. Movement of the latch bolt 13 towards latching position is cushioned by a rubber bumper 17 carried by the case plate, a downwardly bent flange 18 on the latch bolt being engageable with the bumper.

20 Movement of the latch bolt to and from latching position is guided by a rivet 19 secured to the case plate 10 and having its shank disposed in a longitudinally elongate slot 20 formed in the bolt plate 13. Extending rearwardly beyond the rear edge of the case plate 10 is an extension 21 which is integral with the bolt plate 13 and is formed with a longitudinally elongate slot 22 in which rides a pin or rivet 23 fixed to the inner end of a remote control strap or link 24. A spring washer 25 is interposed between the strap 24 and the bolt extension 21. It will be apparent to those skilled in this art that the strap or link 24 leads to the usual remote control device (not shown) having a handle disposed on the inside of the door which by actuation in one direction retracts the latch bolt against the force of the spring 15.

25 Disposed intermediate the bolt plate 13 and case plate 10 is a plate 26 having an opening 27 generally triangular in shape and through this opening extends the rivet 19. At the forward end of the plate 26 is an inwardly extending pin 28 which projects into a downwardly curved slot 29 formed in the case plate 10 and in advance

30 of the pin 28 is an arcuate recess or groove 30 with which engages the rounded end of a roll back 31. The roll back 31 is mounted in the usual manner within a cover plate 32, there being a rectangular opening 33 to receive the squared spindle of an outside operated door handle (not shown). For holding the plate 26 in engagement with the roll back 31, a spiral spring 34 has one end secured to the case plate 10 and its opposite end bearing against a downwardly and rearwardly inclined extension arm 35. It will be apparent that the spring tends to rock the plate 26 in a clockwise direction about the pin 28 as a pivot. Formed at the rear end of the plate 26 is a downwardly inclined cam surface 36 and 35 stepped down slightly from and forwardly of the surface 36 is another cam surface 37, the lower end of which merges into a notch 38. Below the notch 38 is a vertically disposed edge portion 39 which extends inwardly at 40 and merges 20 with a vertically disposed abutment surface 41.

35 In operation it will be apparent that by movement of the strap 24 to the right of Figure 1 by the usual remote control, the latch bolt is retracted against the force of the spring 15, the rivet 23 engaging the rear end of the slot 22, and upon release, the spring returns the bolt nose 12 to latching position. Retraction of the latch bolt from the outside of the door may be effected by turning or rocking the roll back 31 in a clockwise direction, the abutment surface 41 on the plate 26 moving into engagement with a flange 42 on the lower side of the bolt plate extension 21, the retracting movement from the outside of the door thus taking place through the roll back 31, plate 26, and the bolt plate 13.

40 In order to render the outside door handle or roll back 31 inoperative, the remote strap 24 is moved to the left of Figure 1 or in a non-bolt retracting direction. The head of the rivet 23, 40 which is T-shaped, first engages the cam surface 36 of the plate 26 and rocks the plate upwardly and then upon engaging the cam surface 37 a plate is rocked to such position that a shoulder 43 on the upper portion of the plate is moved into 45 abutting relation with the stop 44 on the case plate 10. In this position, the rivet 23 engages in the notch 38 which holds the plate in dogging position. As soon as the strap 24 is moved slightly to the right of Figure 1, the spring 34 50 rocks the plate 26 downwardly moving the shoulder 43 away from the stop 44, thereby enabling retraction of the latch bolt by the roll back 31.

55 It will also be understood that the roll back 31 can be dogged or rendered inoperative by a 55

slide 45 of the usual type actuated by a key-controlled cam (not shown), but since this forms no part of the present invention, further illustration and description will not be given.

- 5 While I have shown and described an embodiment which is the best form known to me at the present time, it is to be understood that numerous changes in details of construction, arrangement and operation may be effected without departing from the spirit of the invention especially as defined in the appended claims.

What I claim is:

1. A vehicle door latch comprising a case plate, a spring-tensioned latch bolt movable over said case plate, inside operated retracting means having lost motion relative to said latch bolt in a non-bolt retracting direction, an outside operated retrector including a plate slidable relative to said case plate, a mounting for said slidable plate affording rocking movements thereof, means on said slidable plate engageable by said inside operated retracting means upon such lost motion for imparting rocking movement to said slidable plate in one direction, and abutment means engageable by said slidable plate upon rocking movement thereof for blocking retracting movement on said outside operated retracting means.
2. A vehicle door latch comprising a case plate, a spring-tensioned latch bolt movable over said case plate, inside operated retracting means having lost motion relative to said latch bolt in a non-bolt retracting direction, an outside operated retrector including a plate slidable relative to said case plate, a mounting for said slidable plate affording rocking movements thereof, means on said slidable plate engageable by said inside operated retracting means upon such lost motion for imparting rocking movement to said slidable plate in one direction, abutment means engageable by said slidable plate upon rocking movement thereof for blocking retracting movement on said outside operated retracting means.

thereof for blocking retracting movement on said outside operated retracting means, and a spring urging said slidable plate away from said abutment means.

3. A vehicle door latch comprising a case plate, a spring-tensioned latch bolt movable over said case plate, inside operated retracting means having lost motion relative to said latch bolt in a non-bolt retracting direction, an outside operated retrector including a plate slidable relative to said case plate, a mounting for said slidable plate affording rocking movements thereof, cam means on said slidable plate engageable by said inside operated retracting means upon such lost motion for imparting rocking movement to said slidable plate in one direction, and abutment means engageable by said slidable plate upon rocking movement thereof for blocking retracting movement on said outside operated retracting means.

4. A vehicle door latch comprising a case plate, a spring-tensioned latch bolt movable to and from latching position relative to said case plate, a pin and slot connection between said bolt and case plate for guiding the movements of the former, a plate interposed between said latch bolt and case plate and provided with an enlarged opening receiving said pin, an outside operated roll back with which said plate engages, a mounting for said plate enabling rocking movements thereof, spring means tending to rock said plate in one direction, an inside operated retrector having a lost motion connection with said latch bolt, a cam surface on said last plate engageable by said inside retrector upon said lost motion for rocking said plate in the opposite direction, and abutment members on said last plate and case plate adapted to be moved into engagement upon rocking movement of said last plate by said inside retrector.

HOLDEN W. RIGHTMYER.
